TAKE-APART SAND TOY BOAT

Sidney A Tarrson, 777 S. Tripp, Chicago, Ill. 60602

Filed Mar. 28, 1969, Ser. No. 16,499

Term of patent 14 years

Int. Cl. D21—02

U.S. Cl. D34—15

Fig.1.

Fig.2.

Fig.3.

FIG. 1 is a perspective view of a take-apart sand toy boat, showing my new design, the opposite side being substantially the same;

FIG. 2 is an elevational view of the end opposite to that shown in FIG. 1;

FIG. 3 is a side elevational view thereof;

FIG. 4 is a bottom plan view thereof;

FIG. 5 is an exploded perspective view thereof showing the parts in disassembled relation.

I claim:

The ornamental design for a take-apart sand toy boat, as shown and described.
